UNITED STATES PATENT OFFICE.

JESSE ALEXANDER, OF BROOKLYN, NEW YORK, ASSIGNOR OF ONE-HALF TO WILLIAM ALEXANDER ALBERT SCHNAUFFER, OF NEW YORK, N. Y.

TYPE-WRITER-RIBBON OPERATING AND FEEDING MECHANISM.

974,334.

Specification of Letters Patent.

Patented Nov. 1, 1910.

Application filed February 18, 1909. Serial No. 478,572.

To all whom it may concern:

Be it known that I, JESSE ALEXANDER, a citizen of the United States, residing at Brooklyn, county of Kings, State of New York, have invented certain new and useful Improvements in Type-Writer-Ribbon Operating and Feeding Mechanism, of which the following is a full, clear, and exact description.

10 My invention relates to improvements in typewriting machines, and is particularly concerned with improvements in the ribbon operating mechanism.

The invention is illustrated as applied to 15 a so-called visible writing machine in which the ribbon is supported upon spools at opposite sides of the machine frame and is caused to travel across the printing point intermittently.

20 The object of the invention is to provide improved means for such intermittent travel of the ribbon which shall be operated at each printing stroke, to provide means to prevent the overthrow of the ribbon and to provide 25 means for shifting the position of the ribbon to correspond with the shifted position of the platen for upper and lower case writing.

With these and other objects in view, the invention consists in the construction and 30 arrangement of parts, a preferred embodiment of which is illustrated in the accompanying drawings, in which,

Figure 1 is a plan view of the machine illustrating my improvements, parts being 35 removed for clear illustration, Fig. 2 is a vertical sectional view on the line 2—2 Fig. 1, looking toward the front. Fig. 3 is a vertical sectional view from front to rear on the line 3—3 Fig. 1. Fig. 4 is a central 40 sectional view on the line 4—4 from front to rear of parts shown in Fig. 3. Fig. 5 is a sectional view on the line 5—5 Fig. 1. Fig. 6 is a detail sectional view of the parts shown in Fig. 5. Fig. 7 is a detached detail 45 view of parts of the ribbon operating mechanism.

The embodiment of my invention herein selected for illustration comprises the machine frame 1 consisting of the usual side 50 plates, upon which is supported a front plate 2 and the type bar segment 3. Upon the front plate 2 and bar segment 3 are arranged the ribbon spool supporting plates 4 which are so mounted as to be readily removed to give access to the ribbon actuating

mechanism. The supporting plates 4 carry the bearings 5, in which the shafts or spindles 6 of the ribbon spools are journaled.

Inasmuch as the spool mechanism on either side of the machine is the same, a description of one will suffice for both.

The ribbon shaft 6 is provided at its lower end with a spool actuating ratchet wheel 7 and upon the upper end of the shaft the spool 8 may be removably keyed in any desired manner. Referring to Fig. 6, means are provided for retaining the spool shaft within its bearing consisting of a cross pin 9 which rests rotatably upon a shoulder 10 at the upper end of the bearing 6. This pin, 70 furthermore, may serve as the means for keying the spool upon the shaft as indicated in Fig. 6. In order to prevent accidental displacement of the spool from its shaft, I provide a stop arm 11, which is fixed upon 75 a post 12 rotatably mounted by means of a spindle 13 in a bearing 14 also carried by the supporting plate 4. The stop arm 11 is normally held by means of a coil spring 15 on the spindle 13 over the upper end of 80 the spool shaft 6 thereby locking the spool thereon when the same is in position. Also mounted upon the post 12 and spindle 13 is a brake arm 16, which, as shown in Fig. 6, 85 is adapted when in normal position to frictionally engage the spool shaft 6, the shoulder 10 of the spool shaft bearing 5 being cut away at 17 to permit such bearing. By this construction too free rotation of the ribbon spool and overthrow thereof is effectually 90 prevented.

To actuate the ribbon spool, a pawl 18 is slidably mounted upon a pin 19 upon the machine frame and is forced outward by a spring 19' toward the ratchet wheel 7, the 95 upper end of which pawl extends across the ratchet wheel 7 and is provided with a resilient ratchet engaging blade or tooth 20, best shown in Fig. 7. Said blade is secured at its lower end to the pawl by the rivets 21 100 and its upper end is held loosely against said pawl by means of a metal strip or ring 22, so constructed as to permit free resilient play of the blade 20 for effectual engagement with the ratchet 7. The object of this 105 construction is to provide a ratchet engaging tooth which may be readily and firmly seated within the teeth of the ratchet wheel but is sufficiently resilient to ride easily over the ratchet teeth upon the return from its 110

actuating stroke. In order to further prevent the overthrow of the ribbon spool, I provide a spring arm 23 Fig. 1 suitably secured to a post 24 depending from the plate 4, the outer end of which spring arm is provided with a tooth 25 arranged to engage the teeth of the ratchet wheel 7 and prevent reverse movement thereof.

To actuate the ratchet pawls 18, the same 10 are pivoted at their rear ends to depending rock arms 26 secured to a rock shaft 27 mounted within one of the supporting bars or tracks 28 of the platen carriage, said bar being provided with openings 29 at its 15 lower side to permit of said rocking movement of the rock arms 26. To actuate the rock shaft 27, the same is provided with a depending lever 30, Figs. 4 and 7, slotted at 31 to receive a pin 32 carried by lug 33 20 depending from the frame 34 which supports the universal bar 35, Fig. 2. In this instance the universal bar is positioned just to the rear of the slots 36 in the type bar segment 3, in which slots the type bars 37 25 are pivoted at 38, as shown in Fig. 4. The universal bar support 34 is pivoted at its rear upon upright rocking frame 37, which in turn is pivoted at its lower end at 38 upon a lug 39 on the machine frame. The 30 upright frame 37 is normally pressed forward by a spring 40, Fig. 3, whereby through the universal bar support 34, the universal bar is yieldingly held in contact with the rear of the type bar segment 3.

35 Each type bar as shown in Fig. 3 is provided with a shoulder 41 which when the bar is in its printing position contacts with the universal bar 35 and serves to move the same to the rear, thereby through the connections between the universal bar support 34 and rock shaft 27, above described, actuating the spool actuating pawls 18 at each printing stroke.

In visible writing machines, to which my 45 invention as herein shown is applied, it is necessary that the ribbon shall stand normally just below the printing point and shall be positioned over the printing point just before the type reaches the platen and 50 then again returned to its normal position. To this end the ribbon support and guide 42 at the center of the machine is pivoted at its lower end to a lever 43, which, in turn, is pivoted at 44 within a depending portion 45 of the platen shift frame 46, which is fixed to a transverse rock shaft 47. Upon the rear of said frame 46 is mounted a roller-carrying arm 48 bearing the roller 49, which is adapted to engage a suitable and usual support of the platen carriage. The rear end 55 of the lever 43 is connected by means of a short link 50 to a post 51 carried by the universal bar support 34. By this construction when the universal bar support is 60 moved to the rear by a type bar the link 43

is rocked upon its pivot 44 by the connections described, thereby raising the ribbon support 42 to position the ribbon over the printing point.

In order to provide for the reversal of 70 the travel of the ribbon at will, a slide bar 52, Fig. 2, is mounted upon screws 53 carried by the type bar segment 3. This bar carries at either end forwardly extending pins 54, which, as shown in Fig. 1, have their forward ends lying adjacent to the inner sides of the ribbon actuating pawls 18, whereby when said slide bar 52 is moved from one side to the other, one of said pins 54 will disengage the corresponding actuating pawl 80 18 from its ratchet and the other pin 54 will be so moved as to permit engagement of the other spool actuating pawl with its ratchet 7. Simultaneously with the disengagement of the pawl 18 from its ratchet 7, 85 the corresponding spring arm 23 is also disengaged therefrom, said arm being provided with an extension 55, Fig. 1, which lies in the path of the ratchet pawl 18, as shown in Fig. 3. For manual operation of the slide bar 52, the same is provided with a depending finger 56, Fig. 2, which may be readily reached by the operator.

In machines employing upper and lower case type, in which the platen is shifted for 95 such upper and lower case printing, it is necessary that the normal position of the ribbon adjacent the printing point be correspondingly shifted in order that the same may be brought to operative position during 100 the printing stroke. To this end, therefore, the lever 43, Fig. 3, which actuates the ribbon support 42 is pivoted upon a depending portion 45 of the platen shift frame 46, as above described, so that when said shift 105 frame is rocked to shift the platen, the lever 43 through its pivot 44 will be moved forward and thus raise or shift the ribbon support 42. The subsequent intermittent actuation of the ribbon support to position the 110 ribbon over the printing point will then take place, as above described.

While the means for shifting the platen forms no part of the present invention, the same is herein illustrated for complete disclosure and consists as shown in addition to the parts above referred to of the rock arms 57 attached to rock shaft 47, which arms are arranged to be actuated by upward extensions 58 of the platen shaft levers 59, the latter being pivoted at 60 upon the machine frame.

While I have herein described a particular embodiment of my invention, it is to be understood the same may be varied in details 125 and relative arrangement of parts without departing from the spirit or scope thereof.

What I claim is:

1. In typewriter ribbon operating mechanism, a pair of ribbon spools, ratchet wheels 130

connected with said spools, actuating pawls for said wheels, each of said pawls carrying a resilient wheel-engaging blade secured at one end of its pawl and free from said pawl at its wheel-engaging portion and means to limit the movement of the free end of said blade with respect to its pawl.

2. In typewriter ribbon operating mechanism, a pair of ribbon spools, ratchet wheels for said spools, actuating pawls coöperating with said wheels, each of said pawls carrying a resilient wheel-engaging blade extending alongside of its supporting pawl; said blade being free from said pawl at its wheel-engaging portion and having limited movement relatively to said pawl at its free end, a universal bar, actuating connections between said bar and said pawls to actuate said ribbon spools.

20 3. In typewriter ribbon operating mechanism, a pair of ribbon spools, ratchet wheels for said spools, an actuating pawl coöperating with each of said wheels, a spring-arm adjacent each of said wheels and adapted to engage the same, means for disengaging and engaging said pawls from and with said wheels at will, and means for causing said pawls simultaneously to disengage and permit the engagement of said spring-arms 30 with the corresponding wheels at will.

4. In typewriter ribbon operating mechanism, a pair of ribbon spools, a ratchet wheel for each of said spools, an actuating pawl for each of said wheels, a spring-arm

coöperating with each of said wheels respectively, an extension on each of said arms projecting transversely of the adjacent pawl, means for engaging and disengaging said pawls from said ratchet wheels, said extensions on said spring-arms being so arranged that the engagement and disengagement of said pawls from said wheels will cause simultaneous engagement and disengagement of said spring-arms with said wheels, respectively.

5. In typewriter ribbon operating mechanism, a pair of ribbon spools, ratchet wheels for said spools, actuating pawls for said wheels, each of said pawls carrying a resilient wheel-engaging blade, said blades being free from said pawls at their wheel-engaging portions, and means to limit the movement of the free portions of said blades away from their respective pawls.

6. In typewriter ribbon operating mechanism, a pair of ribbon spools, ratchet wheels for said spools, actuating pawls for said wheels, each of said pawls carrying a flexible wheel-engaging blade, said blades being free from said pawls at their wheel-engaging portions, a band surrounding each of said pawls and its resilient blade to limit the movement of said blade away from said pawl.

JESSE ALEXANDER.
